CAN WRAPPING AND LABELING MACHINE

Josef F. Mose, Point Loma, Calif.

Application November 29, 1933, Serial No. 700,237

11 Claims. (Cl. 93—2)

My invention relates to can wrapping and labeling machine, and the objects of my invention are:

First, to provide a machine of this class which 5 is particularly adapted to wrap and label oval cans.

Second, to provide a machine of this class which is adapted to operate in conjunction with any suitable conveying arrangement adapted to 10 deliver an oval can, and the wrapper, in superposed centered relation.

Third, to provide a machine of this class which incorporates a novel means of applying a label to the wrapped can in such a manner as to hold 15 and cover the edges of the wrapper.

Fourth, to provide a machine of this class which incorporates a novel means for holding the margins of a paper over the top of the can in such a manner as to leave an open space into which 20 the margins of the wrapper project so that a label may be inserted therein.

Fifth, to provide a machine of this class so arranged that the margins of the wrapper may be 25 gummed and in a sticky condition when delivered to the machine so that the wrapper is held not only by the adhesion of its gummed portion to the can but also by the label, the machine however being adapted to secure a wrapped can even though the wrapper is without adhesive.

Sixth, to provide a machine of this class which is adapted to operate with a minimum amount of attention and which is so arranged that a fresh supply of labels may be added from time to time 30 without stopping the machine; and

Seventh, to provide on the whole a novelly constructed can wrapping and labeling machine which is durable, efficient in its action, and which will not readily deteriorate or get out of order.

With these and other objects in view as will 40 appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a plan view of my can wrapping and labeling machine with parts and portions broken away and removed or in section to facilitate the illustration and with the various moving parts in the positions assumed at the finish of the labeling operation; Fig. 2 is an enlarged fragmentary plan view of the can receiving portion with the wrapper margin folding plates in their open or

receiving position; Fig. 3 is a sectional view substantially through 3—3 of Fig. 1 showing certain of the cams used in the operation of the various moving parts and illustrating these parts in the positions assumed when a can and its wrapper is 5 being delivered to the machine; Fig. 4 is a sectional view of the main cam shaft taken through 4—4 of Fig. 5 with the several parts illustrated in positions corresponding to those illustrated in Fig. 3; Fig. 5 is an enlarged fragmentary sectional 10 view through 5—5 of Fig. 1 with parts and portions in elevation and with the various moving members in their positions assumed during the labeling operation; Fig. 6 is another enlarged sectional view taken through 6—6 of Fig. 1 with parts 15 and portions as shown in elevation; Fig. 7 is a fragmentary detailed sectional view through 7—7 of Fig. 6; Fig. 8 is an enlarged fragmentary plan view of a carriage member adapted to supply an oval can and its wrapper to the machine; Fig. 20 20 9 is a fragmentary perspective view of the can receiving member and its adjacent portions with the wrapper margin folding members removed and reduced and the other members in the positions assumed when ejecting the wrapped can; Fig. 10 is an enlarged fragmentary sectional view 25 through 10—10 of Fig. 1 with parts and portions as shown in elevation and with the several moving members in the positions assumed when the label carriers are midway in their return movement; Figs. 11 to 15 inclusive are diagrammatical 30 views illustrating the various steps performed by the machine; Fig. 11 illustrates the upper and lower plungers in the act of removing the can and wrapper from the feeding mechanism; Fig. 12 illustrates the manner in which the margins of the wrapper are directly upwardly around the margins of the can; Fig. 13 illustrates the manner in which the margins of the wrapper are 35 folded over the top of the can and the label is applied; Fig. 14 illustrates the manner in which an opening is provided for the ejection of the can; and Fig. 15 illustrates the ejecting operation.

Similar characters of reference refer to similar 45 parts and portions throughout the several views of the drawings.

Framework 1, table 2, can receiving frame 3, gate member 4, operating rod 5, cam follower 6, cam 7, cam shaft 8, bottom plunger 9, operating 50 rod 10, cam rider wheel 11, bottom plunger cam 12, ejector lever 13, cam rider 14, ejector cam 15, spring 16, wrapper margin folding plates 17, 18 and 19, guide pins 20, pin 21, bracket 22, levers, operating member 24, cam rider 25, folding plate 55

cam 26, upper plunger 27, label holding means 28, yieldable cover 29, rod 30, lever 31, shaft 32, connecting means 33, guide 34, lever 35, shaft 36, cam rider 37, under plunger cam 38, countershaft 39, 5 sprocket and chain means 40, bearings 41, segmental spur gear 42, pinion gear 43, shaft 44, bearing caps 45, label carriers 46, guide member 47, brackets 48, carrier return members 49, segmental bevel gears 50, springs 51, adhesive supplying rollers 52, adhesive receptacles 53, label support 54, sleeve 55, guide 56, rod 57, tension spring 58, roller 59, lever 60, cam rider 61, cam 62, return spring 63, carriage frame 64, can gripping member 65, springs 66, arms 67, wheels 68, track 69, levers 70 15 and 71, push rod 72, and spring 73, constitute the principal parts and portions of my novel can wrapping and labeling machine.

A framework 1 is provided which may be common to the feeding mechanism used in conjunction with my can wrapping and labeling machine, such feeding mechanism being omitted from the drawings. The framework 1 includes side members 1a which support therebetween a table 2. At one side of the table, midway between the side 25 members 1a, there is provided a can receiving frame 3, which may be formed integral with the table 2. The can receiving frame 3 projects above the normal level of the table 2 and is provided with a centrally disposed oval shaped recess 3a, 30 disposed with its longest axis lengthwise with the machine, that is parallel to the side members 1a. One entire longer side of the recess 3a is cut away so as to form a gateway 3b intersecting a side of the can receiving frame 3. The gateway extends 35 below the normal bottom of the recess 3a and is adapted to receive a gate member 4. The gate member 4 is complementary to the oval recess 3a, that is its inner side is semi-oval and when the gate is in its upper position entirely closes the 40 gateway 3b. The gate member 4 shifts from a position below the normal bottom designated 3c of the can receiving recess to a position in which the upper side of the gate is flush with the top of the can receiving frame as shown in Figs. 3 and 5. 45 A centrally disposed operating rod 5 extends downwardly from the gate 4 through a suitable guide 2a depending from the table 2 and terminates in a bearing which supports a cam follower 6. The cam follower operates in a cam channel 50 formed in a gate operating cam 7. The cam 7 is mounted on a cam shaft 8 which is driven by any suitable means not shown and is disposed transversely with the framework so as to extend underneath the can receiving frame 3.

55 The oval-shaped bottom portion 3c of the can receiving frame is in turn provided with an oval-shaped recess in which is mounted the flat head of a bottom plunger 9, as shown in Figs. 5, 6 and 9. The can receiving frame or the table supports 60 a guide 2b mounted below and in centered relation to the bottom plunger so as to receive a depending operating rod 10, which extends downwardly beyond the guide 2b and is provided with a bearing for supporting a cam rider wheel 11, 65 adapted to operate in a groove or channel formed in a bottom plunger operating cam 12 mounted on the cam shaft 8.

A bracket 2c extends laterally from the guide 2b and is adapted to hinge a cam ejector lever 13. 70 The lever 13 comprises an outwardly extending portion 13a terminating in an arcuate arm portion 13b having a curvature concentric with the axis of rotation of the lever. The extremity of the curved arm 13b is provided with a cross member

13c which fits in and conforms with a slot 3d formed in the sidewall of the recess 3a opposite from the gateway 3b as shown best in Fig. 9. The ejector lever normally occupies a position in which the cross portion 13c is substantially flush with 5 the sidewall of the recess 3a as shown in Fig. 5. The ejector lever is provided with an arm 13e which extends outwardly and downwardly from the bracket 2c and is provided with a cam rider 14. The cam rider 14 rides upon an ejector operating cam 15 which may be formed integrally with the bottom plunger cam 12. The ejector operating cam 15 in such a case is formed on the opposite side of the cam 12 from its channel as shown best in Fig. 5 and is in the form of annular 15 track the surface of which extends radially with respect to the axis of the ejector lever at the portion engaged by the cam rider 14. A substantially axially extending boss 15a acts to shift the ejector lever to the dotted line position shown in Fig. 5. 20 The ejector lever is held against its cam by means of a coil spring 16, which may be associated with the bracket 2c, as shown best in Fig. 7.

The marginal portions of the can receiving frame 3 surrounding the recess 3a, as well as the 25 top of the gate 4, is covered by wrapper margin folding plates 17 and 18, and 19. The plates 17 and 18 are positioned adjacent the can receiving frame 3 and are hinged together at their one ends by means of a swivel bracket 21. These plates 30 are similar in form and are adapted to extend from their connected ends around opposite sides of the recess 3a, their inner edges designated 17a and 18a being curved to approximate the form of the recess 3a. The extremities of the plates 17 35 and 18 are provided with angularly disposed slots 17b and 18b, through which extend guide pins 20, fastened into the can receiving frame 3. The slots 17b and 18b are so arranged that when the secured ends of the plates 17 and 18 are shifted toward the recess 3a, the extended ends of said plates move toward each other so that the curved inner margins 17a and 18a of the plates overlap the margins of the recess 3a as shown in Figs. 1, 5 and 6. 45

The plate 19 fits on top of the plates 17 and 18 and is substantially co-extensive with the top of the can receiving frame 3. The plate 19 is provided with an oval-shaped aperture 19a which is somewhat larger than the recess 3a, so that 50 when the plate 19 is centered with respect to the recess, the margins thereof are exposed as shown in Fig. 2. The plate 19 is provided with slots 19b at one end and a slot 19c at its opposite end disposed parallel with the longer axis of 55 the recess 3a. The slots 19b receive the guide pins 20 while the slot 19c receives the shank of the swivel bracket 21. The latter slot is of sufficient length to permit the relative movements of the several plates. The end of the plate 19 having the pair of slots 19b is provided with a depending bracket 22, corresponding to the swivel bracket 21. The two brackets are connected to corresponding ends of a pair of levers 23, as shown best in Fig. 6. The levers 23 are L-shaped 60 and are journaled intermediate their ends from lugs 3e, extending outwardly and downwardly from the can receiving frame 3. The remaining legs, designated 23a, of the levers 23 extend toward each other and are joined to a connecting bar 24a of an operating member 24. The connecting bar 24a passes around the guide 2b and one end thereof is provided with a depending rod 24b, which extends downwardly through a guide 2d supported from the side of the guide 2b. 75

The lower end of the rod 24b supports a cam rider 25, which is adapted to operate in a channel formed in a cam member 26. The cam member 26 is mounted between the cams 7 and 12 on the shaft 8.

When the plates 17, 18, and 19 are shifted toward each other by action of the levers 23, they together delineate an oval-shaped aperture which is centered with respect to the depression or recess 3a but which is less in diameter.

Mounted above the recess 3a and in centered relation therewith is an upper plunger 27, which conforms in shape to but is slightly smaller than said recess. A longitudinal slot 27a is formed in the plunger 27 which receives a bar 28a forming a part of a label retaining means 28. Guide pins 28b extend upwardly from the bar thru the plunger, and are secured to a cross plate 28c which is provided with a centered opening. A boss 27b of the plunger extends upwardly through the cross plate 28c. A guide rod 30 is secured in the boss and secures a collar 30a to the upper end of the boss, said collar is provided with a pair of diagrammatically disposed journal lugs 30b, one of which is engageable by a catch lug 28d pivotally supported from the plate 28c. A spring 28e tends to force the catch into engagement with its pin, such connection being made when the bar is in its retracted position. Another spring 28f extending between the collar 30a and cross plate 28c tends to force the bar to an extended position. A yieldable cover 29, preferably formed of rubber covers the bottom face of the plunger 27 and bar 28a.

The rod 30 extends upwardly and through a guide 1b which is supported on a cross member 1c forming a part of the framework 1. The guide 1b carries a lug 1d. The catch 28d has an arm 28g. The lug and arm engage when the plunger reaches its extreme upper portion to release the catch 28d.

The journal pins 27e fit in slots provided in a yoke 31a mounted at the extremity of a lever 31. The lever 31 extends upwardly and away from the rod 30 and is journaled on a shaft 32 supported from the framework 1. The other or remaining arm 31b of the lever 31 continues from the shaft 32 and is connected to the upper end of a connecting means 33.

The connecting means includes a rod 33a which extends downwardly through a guide 34 supported from the framework 1. The rod 33a terminates in a socket 33b into which fits a second rod 33c. The rod 33c and socket 33b are limited in their relative axial movement by means of a slot and pin arrangement 33d. Shoulders are provided on the rods 33a and 33c, between which is disposed a stiff spring 33e of greater strength than the spring 28f between the retaining means 28 and the upper plunger 27. The lower end of the rod 33c is connected to one arm of a lever 35 which is journaled intermediate its ends upon a shaft 36 also supported from the framework 1 in any suitable manner not shown. The remaining arm of the lever 35 is provided at its extremities with a cam rider 37 which is adapted to fit in a suitably formed channel provided in the side of a cam 38 mounted on the shaft 8. The arm 31a of the lever 31 is preferably offset laterally with respect to the other arm of said lever in as much as the cam 28 is offset laterally with respect to the axis of the upper plunger.

The main or cam shaft 8 drives a countershaft 39 by means of a chain and sprocket means 40.

The countershaft 39 is hung from the table 2 by means of bracket bearing 41, and supports a centrally positioned segmental spur gear 42.

Above the segmental spur gear 42, the table 2 is raised forming a platform 2e which is centered with respect to the can receiving frame and extends outwardly at one end thereof. The platform 2e is provided with a slot 2f which continues to the can receiving frame 3 so that the bracket 22 and its lever may extend downwardly therethrough as shown in Fig. 6.

The slot 2f is adapted to receive a pinion gear 43 which is adapted to engage the teeth of the segmental spur gear 42. The pinion gear 43 is keyed on a shaft 44 which extends across the platform 2e in bearings 2g formed therein over which are the bearing caps 45. The extremities of the shaft 44 protrude slightly beyond the platform 2e at both ends and are joined at the opposite ends by hinges 46a to arms 46b of label carriers 46 of which there are two oppositely disposed. Each label carrier 46 is provided at the extremity of its arm 46b with a pair of oppositely disposed label carrying plates 46c, shown best in Fig. 1 of the drawings, one extending laterally from the top side of the arm 46b and the other extending laterally from the bottom side of said arm 46b. Therefore, there is provided one label carrying plate 46c on each arm 46b which cooperate for carrying a label, and the other plate 46c cooperates in the opposite direction for carrying a label to the other can. Each label carrying plate is arcuate in form and of such a size as to fit within and adjacent the margins of the wrapper margin folding plates, when said plates are in their contracted or inner positions. The upper plates of the two carriers are complementary and work together to place a label on each side of the can at the left side of Fig. 1, as do also the lower plates place a label on each side of the can at the right side of Fig. 1. During their carrying movement, the arms 46b extend at right angles to the shaft 44 and thereby rotate about a horizontal axis from a position at the side of the platform 2e, remote from the can receiving frame to a position in which the co-acting pair of plates 46c register with the aperture 3a. On return movement, the carriers rotate about a vertical axis; that is in a horizontal plane. In order to guide the arms 46b in such movement, the bearing caps 45 are provided at their extremities with upwardly extending guide walls 45a, which coact with guide walls 47a of guide members 47. The guide members 47 are supported from the side members 1a and extend inwardly therefrom over the table 2 in spaced relation thereto so that the guide walls 47a form with the guide walls 45a a pair of slots as shown best in Figs. 1 and 10. These slots designated A guide the arms while they rotate about a horizontal axis. The table 2 at either side of the platform 2e is provided with semi-circular slightly elevated guide portions 2h, which coact with corresponding guide portions 47b provided on the under side and at the extremities of the guide members 47, thus the guide portions 2h and 47b form horizontal guide slots B.

Secured to the under side of the platform 2e on either side of the pinion gear 43 are a pair of brackets 48 which extend downwardly and outwardly and terminate in upwardly directed spindles 48a, having their axes in approximate alignment with the center of movement of the hinge members 46a. Journaled upon each spindle 48a is a carrier return member 49 which

comprises an arm 49a terminating in an upwardly directed pin 49b which projects through an arcuate slot 27 on the raised guide portion 2h and terminates in a roller 49c. The rollers 49c are adapted to engage the sides of the arms 46b and shift them laterally away from the can receiving frame in the direction of the arrows shown in Fig. 1. The carrier return members 49 are provided with segmental gear portions 49d which are adapted to engage segmental bevel gears 50 mounted on the countershaft 39. Springs 51 are provided which connect with the carrier return members in such a manner as to return said members to their starting position as soon as the segmental gear portions 49d are disengaged by the segmental bevel gears 50.

The lowermost label carrying plates 46c of the label carriers engage adhesive supplying rollers 52 during their return movement. The rollers 52 are mounted in receptacles 53 which are set into the table 2 shown best in Fig. 5.

Underneath the position occupied by the lower pair of label carrying plates when the label carriers are in their extreme return position, there is mounted a label support 54, which comprises a platform 54a with upwardly directed guide walls 54b suitably spaced so as to retain a stack of labels designated L, as shown in Fig. 3. The support is mounted on a sleeve 55 which extends downwardly through a guide 56 supported from the framework 1. A rod 57 extends upwardly into the sleeve 55 and is provided at its lower or protruding end with a roller 59. Between the inner extremity of the rod 57 and the inner end of the sleeve 55, there is mounted a tension spring 58. The roller 59 engages one end of the lever 60 which is fulcrumed intermediate its end upon the shaft 36. The remaining arm of the lever 60 is provided with a cam rider 61 which engages the periphery of a cam 62 mounted on the cam shaft 8, as shown best in Fig. 4. A spring 63 is disposed between the extremity of the rod 57 and the guide 56 and tends to maintain the roller 59 upon the lever 60, and consequently holds the rider 61 against the cam 62.

The can and wrapper is delivered to the wrapping and labeling machine by means of a carriage or the like such as illustrated in Fig. 8. The carriage comprises an oval shaped frame 64, the underside of which is adapted to be coated with an adhesive or to be moistened so as to adhere to adhesive provided around the margins of an oval shaped wrapper W, the adhesive indicated by the character W1. The frame 64 supports a pair of gripping members 65 which are adapted to engage opposite sides of an oval shaped can designated C; such gripping members being held securely against the sides of the can by means of springs 66. These springs surround shafts extending outwardly from the fingers through suitable guides 64a provided in the frame 64. The frame 64 is provided with arms 67 which terminate in wheels 68 or the like adapted to ride upon tracks 69 shown fragmentarily in Fig. 1. This construction may be similar to the feeding arrangement illustrated in my former patent for can wrapping and key placing machine, Patent No. 1,843,458. Of course any other suitable mechanism capable of supplying the can and wrapper in superposed centered relation may be used in conjunction with the present machine.

Operation of my machine is as follows: A suitable carriage member delivers the wrapper with the can thereabove into centered relation with the recess 3a, the lower plunger 9 and upper

plunger 27 are then shifted toward the can and wrapper and engage the same. Whereupon the two plungers move downwardly together pulling the adhesive coated marginal portion W1 of the wrapper away from the carriage. Downward movement of the plungers into the recess 3a causes the margins of the wrapper to be folded upwardly as shown in Fig. 12; the upper plunger 27 then moves upwardly until it is clear of the label carriers 46 as shown in Fig. 13. These two members are rotated in a horizontal axis with a pair of the label carrying plates in complementary relation and carrying a label designated L. During this movement, the margin folding plates 17, 18 and 19, move toward each other so that their inner curved edges engage the protruding portions of the wrapper and force them inwardly over the top of the can C as shown in Fig. 13, and also indicated in Figs. 5 and 6. The label carriers bring the label into superposed relation with the can, the label being sufficiently small in area to fit within the aperture delineated by the plates 17, 18 and 19 when in their inner positions. The upper plunger then returns to its lower position shown by dotted lines in Fig. 3, which is similar to the position shown by solid lines in Fig. 5, whereupon the bar 28a presses the central portion of the label firmly against the can. This movement of the upper plunger is such that its marginal portion 27b does not bear against the label carrying plate. It should be noted here that the movable bar 28a fits within the oval shaped space formed by the complementary pairs of label carrying plates. While the label is held by the tension of the bar 28a against the can, the carriers are started out on their return movement and therefore pull under the label. As soon as this is accomplished, a slight additional movement of the upper plunger causes the marginal portion 27b thereof to press firmly against the can, and causing the catch to lock the bar with retracted position until the plunger is again raised to its extreme upper position. Thereupon the upper plunger again raises part way, as shown in Fig. 14, and at the same time the gate 4 moves downwardly. The end of the ejector lever 13 moves inwardly, as shown in Fig. 15 so as to push the can out of the gateway 3b and on to a suitable chute 2k supported from the table 2.

As soon as the ejector lever 13 returns to its position, the bottom plunger 9 is on upward movement and another can and its wrapper is delivered between the upper and lower plungers.

During the period following the return movement of the label carrier, and before they again start on their operating movement, the label support 54 is shifted upwardly by action of the lever 60 and can 62 until the uppermost label engages the lower pair of these plates, being the ones in complementary relation. This pair of plates has received adhesive, when said plates passed over the adhesive applying roller 52 during the return movement of the label carriers. The tension spring 58 enables the label support 54 to stop whenever the labels engage the label carrying plates. In order to retain these plates in position against the action of the tension spring pressing upwardly thereon, there is provided a pair of levers 70 and 71, suitably supported from the frame 1 in such a manner as to be engaged by a push rod 72 supported from the lower end of the rod 57 as shown best in Fig. 3. The lever 70 is normally held out of the road by means of a spring 73.

Though I have shown and described a particular construction, combination and arrangement of parts and portions, I do not wish to be limited to this particular construction, combination and arrangement, but desire to include in the scope 5 of my invention the construction, combination and arrangement substantially as set forth in the appended claims.

Having thus described my invention, what I 10 claim as new and desire to secure by Letters Patent is:

1. In a can wrapping and labeling machine for a can and its wrapper in superposed centered relation, the combination of means for simultaneously directing the entire margins of the wrapper over the edges of the can whereby the wrapper projects beyond the opposite side thereof, mechanism for simultaneously folding the projecting portions inwardly against the can, a label carrier, 15 means for adhering a label thereto, said label carrier arranged to apply said label to said can so as to cover the inwardly extending margins of said wrapper, and means for pressing said label in place while said label carrier is withdrawn.

25 2. In a can wrapping and labeling machine for a can and its wrapper in superposed centered relation, the combination of a wrapper and can receiving frame including a recess conforming to the shape of said can whereby upon insertion 30 of said can therein, the margins of the wrapper are directed over the edges of said can and extended beyond the opposite side of said can, and a constrictable ring means surrounding said recess and arranged to engage the protruding portions of said wrapper and direct them inwardly against said can, a label carrier, and means for adhering a label thereto, said label carrier arranged to apply said label within said ring means so as to cover the inwardly extending margins 35 of said wrapper, and means for pressing said label in place while said label carrier is withdrawn.

40 3. In a can wrapping and labeling machine for a can and wrapper in superposed centered relation, the combination of a wrapper and can receiving frame including a recess conforming to the shape of a can, means for removing said can and wrapper from said delivering means and inserting the same in said recess whereby the margins of the wrapper are directed over the edges of 45 said can and project beyond the opposite side thereof, folding mechanism arranged to shift inwardly over said opposite side of the can and fold the protruding margins inwardly against the can, a label carrier, means for adhering a label thereto, said label carrier arranged to apply said label to said can so as to cover the inwardly extending margins of said wrapper, and means for pressing said label in place while said label carrier is withdrawn.

45 4. In a can wrapping and labeling machine for a can and wrapper in superposed centered relation, the combination of a wrapper and can receiving frame including a recess conforming to the shape of a can, means for removing said can and wrapper from said delivering means and inserting the same in said recess whereby the margins of the wrapper are directed over the edges of said can and project beyond the opposite side thereof, folding mechanism arranged to 50 shift inwardly over said opposite side of the can and fold the protruding margins inwardly against the can, a label carrier, means for adhering a label thereto, said label carrier arranged to apply said label to said can so as to cover the inwardly extending margins of said wrapper, means

5 for pressing said label in place while said carrier is withdrawn, and driving elements for said removing means, folding mechanism, label carrier, and label pressing means for causing their operation in sequential order.

5 5. In a can wrapping and labeling machine for a can and wrapper in superposed centered relation, the combination of a frame having a recess arranged to receive said can, the side walls of said recess arranged to engage and fold the marginal portions of the wrapper against the edges of the can whereby the extremities of the wrapper project beyond the opposite side, a gate forming a portion of said side walls, a chute leading from said gate, folding means disposed so as to move 10 inwardly across and adjacent the other side of said can and arranged to engage the marginal extremities of said wrapper and fold the same against the can, means for applying a securing member to said can so as to cover the extremities of said wrapper, and an ejector carried by said frame arranged to push the wrapped can through said gate.

25 6. In a can wrapping and labeling machine for a can and wrapper in superposed centered relation, the combination of a frame having a recess arranged to engage and fold the marginal portions of the wrapper against the edges of the can whereby the extremities of the wrapper project beyond the opposite side, a gate forming a portion of said side walls, a chute leading from said gate, folding means disposed so as to move 30 inwardly across and adjacent the other side of said can and arranged to engage the marginal extremities of said wrapper and fold the same 35 against the can, means for applying a securing member to said can so as to cover the extremities of said wrapper, an ejector carried by said frame arranged to push the wrapped can through said gate, and mechanism connected with the folding 40 means, gate and ejector for causing sequential operation thereof.

7. In a can wrapping and labeling machine, a pair of plungers arranged to engage and hold a flat can and its wrapper therebetween with 45 the margins of the wrapper extending outwardly around the can, a frame, said plungers arranged to carry said can and its wrapper into said frame, the side walls of said frame conforming to the edges of the can whereby upon movement of said 50 can and wrapper therein the margins of the wrapper are folded against the edges of the can so as to protrude beyond the opposite side thereof, constrictible ring means surrounding said can contiguous to said opposite side and arranged to 55 engage the protruding portions of said wrapper and fold them inwardly against the can, and means for applying a securing member to said can and the extremities of said wrapper.

60 8. In a can wrapping and labeling machine, a pair of plungers arranged to engage and hold a flat can and its wrapper therebetween with the margins of the wrapper extending outwardly around the can, a frame, said plungers arranged to carry said can and its wrapper into said frame, 65 the side walls of said frame conforming to the edges of the can whereby upon movement of said can and wrapper therein the margins of the wrapper are folded against the edges of the can so as to protrude beyond the opposite side thereof, constrictible ring means surrounding said can contiguous to said opposite side and arranged to 70 engage the protruding portions of said wrapper and fold them inwardly against the can, means for applying a securing member to said can and 75

the extremities of said wrapper, a gate forming a portion of the side walls of said frame, adapted to shift away from the edge of the can to form a discharge aperture, and an ejector adapted to push the wrapped can through said aperture.

5. In a can wrapping and labeling machine, a pair of plungers arranged to engage and hold a flat can and its wrapper therebetween with the margins of the wrapper extending outwardly around the can, a frame, said plungers arranged to carry said can and its wrapper into said frame, the side walls of said frame conforming to the edges of the can whereby upon movement of said can and wrapper therein the margins of the wrapper are folded against the edges of the can so as to protrude beyond the opposite side thereof, constrictible ring means surrounding said can and wrapper therein the margins of the wrapper are folded against the edges of the can so as to engage the protruding portions of said wrapper and fold them inwardly against the can, a label carrier, means for adhering a label thereto, said label carrier arranged to apply said label to said can so as to cover the inwardly extending margins of said wrapper, and means for pressing said label in place while said label carrier is withdrawn.

9. In a can wrapping and labeling machine, a pair of plungers arranged to engage and hold a flat can and its wrapper therebetween with the margins of the wrapper extending outwardly around the can, a frame, said plungers arranged to carry said can and its wrapper into said frame, the side walls of said frame conforming to the edges of the can whereby upon movement of said can and wrapper therein the margins of the wrapper are folded against the edges of the can so as to protrude beyond the opposite side thereof, constrictible ring means surrounding said can and wrapper therein the margins of the wrapper are folded against the edges of the can so as to engage the protruding portions of said wrapper and fold them inwardly against the can, a label carrier, means for adhering a label thereto, said label carrier arranged to apply said label to said can so as to cover the inwardly extending margins of said wrapper, and means for pressing said label in place while said label carrier is withdrawn.

10. In a can wrapping and labeling machine, a pair of plungers arranged to engage and hold a flat can and its wrapper therebetween with the margins of the wrapper extending outwardly around the can, a frame, said plungers arranged to carry said can and its wrapper into said frame, the side walls of said frame conforming to the edges of the can whereby upon movement of said can and wrapper therein the margins of the wrapper are folded against the edges of the can so as to protrude beyond the opposite side thereof, constrictible ring means surrounding said can and wrapper therein the margins of the wrapper are folded against the edges of the can so as to engage the protruding portions of said wrapper and fold them inwardly against the can, a label carrier, means for adhering a label thereto, said label carrier arranged to apply said label to said can so as to cover the inwardly extending margins of said wrapper, and means for pressing said label in place while said label carrier is withdrawn.

contiguous to said opposite side and arranged to engage the protruding portions of said wrapper and fold them inwardly against the can, a label carrier, means for adhering a label thereto, said label carrier arranged to apply said label to said can so as to cover the inwardly extending margins of said wrapper, means for pressing said label in place while said label carrier is withdrawn, and driving mechanism including elements connected with the plungers, ring means, label carrier and the several means, so as to cause their operation in sequential order.

11. In a can wrapping and labeling machine, a pair of plungers arranged to engage and hold a flat can and its wrapper therebetween with the margins of the wrapper extending outwardly around the can, a frame, said plungers arranged to carry said can and its wrapper into said frame, the side walls of said frame conforming to the edges of the can whereby upon movement of said can and wrapper therein the margins of the wrapper are folded against the edges of the can so as to protrude beyond the opposite side thereof, constrictible ring means surrounding said can and wrapper therein the margins of the wrapper are folded against the edges of the can so as to engage the protruding portions of said wrapper and fold them inwardly against the can, a label carrier, means for adhering a label thereto, said label carrier arranged to apply said label to said can so as to cover the inwardly extending margins of said wrapper, and means for pressing said label in place while said label carrier is withdrawn.

JOSEF F. MOSE.
